Attorney

UNITED STATES PATENT OFFICE

THEODORE J. MILLER, OF EL CAMPO, TEXAS

OIL-WELL DELIVERY APPARATUS

Application filed March 24, 1927. Serial No. 178,041.

This invention relates to oil well delivery apparatus, and particularly to means for unsealing a sealed portion of the well lying below the well casing as the pipe string is lowered to tap the oil strata at progressively deeper levels, and also for maintaining the bore of the well below the pipe screen free of detritus in order to prevent clogging of the well and to ensure an unrestricted flow 10 of the oil to the surface.

The main object of the invention is to provide means for the purpose described which is simple of construction, reliable and efficient in action, economical in construction and use, 15 and which may be operated for unsealing purposes or to clear the bore of obstructions to oil flow by simply rotating the pipe string.

Another object of the invention is to provide a reamer-like device for the purpose described which is adapted to be attached to the pipe string in advance of the screen and by means of which a mud sealing wall may be progressively cut away or detritus loosened, said device being channeled to facilitate the 20 discharge of all deposits liable to interfere with the free flow of oil.

The invention consists of the features of construction, combination and arrangement of parts, hereinafter fully described and 25 claimed, reference being had to the accompanying drawing, in which:—

Figure 1 is a vertical section through an oil well showing the application of the invention.

Figure 2 is a vertical longitudinal section of the reamer.

Figure 3 is a view in elevation thereof.

In the practical embodiment of the invention as herein disclosed, 1 designates a well bore, 2 the well casing, 3 a pipe string extending downward through the well casing and through which the oil from the oil bearing strata flows to the surface, and 4 a screen or strainer arranged at the lower end of the pipe string. This screen or strainer may be a perforated portion of the pipe, or formed independently of the pipe and secured thereto, or of any of the constructions in common use or any suitable construction designed for the purpose. 5 is a sealing wall formed, as

usual, of mud or other material, employed in the well bore below the casing to prevent the walls of the bore from breaking down and closing the bore, and also for sealing the oil bearing strata below the point which is tapped for the extraction of oil.

In carrying my invention into practice I provide a cutting tool or reamer adapted for attachment to the lower end of the pipe string to operate in advance of the screen 4, whereby portions of the wall 5 may be progressively removed for unsealing actions, and whereby also the bore below the well casing may be freed from detritus. This tool comprises a body 6 of circular cross-section, and of a diameter corresponding substantially to the external diameter of the pipe string 3 and internal diameter of the sealing wall 5. This body is formed with a tapered lower end portion 7 and an externally threaded upper end portion 8, the latter being adapted for engagement with internal threads on the pipe screen 4, whereby the tool 6 is attached as a fixture to the pipe string. Formed in the circular body portion of the tool is an annular series of vertical recesses 9, parallel with the axis of the tool, in each of which is arranged a cutter 10. The cutters 10 are pivotally mounted at their lower ends, as indicated at 11, at the lower ends of the recesses so as to swing outwardly and inwardly, and springs 12, seated in the upper ends of the recesses, are provided to bear upon the upper ends of the cutters and to force said upper ends of the cutters outwardly. The cutters are provided with outer longitudinal cutting edges 13 and terminate at their upper end in angularly bent or obliquely arranged portions 14 presenting at their points of intersection with the edges 13 contact shoulders 14'. The springs 12 are arranged to bear against the inner faces of the portions 14 so as to dispose the cutting edges 13, when the cutters are free for projection outward, whereby the cutting edges diverge in an upward or rearward direction and project, in the advancing cutting motion of the cutters, to a progressively increasing degree beyond the surface of the body 6 for a gradual cutting action and so as to cut with a draw-cut on a tapering

line. Each cutter is provided with a clearance bore or passage 15 of uniform diameter throughout its portions 6 and 7 of an enlarged diameter at its upper end, in the cutter portion 8, through which bore any liquid or substance lying in the well bore below it may pass upwardly into the pipe string and through the latter to the surface.

In use, the tool is attached to the perforated or strainer end of the pipe string and is lowered therewith down through the well casing until it passes beyond the lower end of the casing, in which operation the shoulders 14' of the cutters 10 ride in contact with the interior surface of the pipe casing, thus holding the cutters retracted until they pass the lower end of the pipe casing, whereupon the cutters are projected by their springs 12. The tapered end 7 of the cutter will then enter the upper end of the sealing wall 5 and form a guide to center the cutter and the pipe string in the well, and then by rotating the pipe string in the proper direction, the cutter or reamer will be actuated to cause the edges 14 of the blades to cut away a desired portion of the upper end of the wall 5 clear of the line of the well bore for the purpose of unsealing a corresponding portion of the oil bearing strata. In this cutting action the edges 13, by reason of the inclined position of the cutters 10, form a tapered cutter which effects a gradual cutting away of the wall as the reamer advances, whereby a ready and easy cutting action is effected. The strainer 4 is so related to the cutter or reamer that the strainer may be brought to lie opposite the unsealed portion of the bore, for the flow of oil thereinto and up through the pipe string, while the cutter rests inactively within a partially cut away portion of the wall 5 beneath it, so that only that portion of the well bore which is tapped will be exposed and put into communication with the pipe string, while the portion of the bore below it and bounded by the wall 5 will be stoppered or closed by the reamer or cutting tool. From time to time, as occasion requires, the pipe string may be rotated for cutting away the wall 5 to expose new portions of the oil bearing strata, thus enabling portions of the sealed part of the well to be unsealed when desired, and the sealed portion kept constantly closed. The threads upon the strainer and reamer may be either right hand or left hand threads as desired, so that by turning the pipe string in the proper direction the reamer may be rotated for a cutting action, while by turning the pipe string in the opposite direction it may be unscrewed from the reamer for independent removal from the well casing. When a pipe string is thus removed, the tool may be allowed to remain as a plug or stopper, as will be readily understood, which may be rotated for unsealing or clearing actions on the re-insertion of a pipe

string and its re-engagement therewith. The reamer may, however, be removed with the pipe string, if desired, by leaving it connected with the pipe string while the latter is being withdrawn, in which event the outer edges of the angular portions 14 of the cutters will serve as beveled retracting surfaces which, upon engagement with the lower end of the pipe tubing, will force the cutters inwardly to a retracted position, the contact surfaces 14' thereupon riding in contact with the well tubing and protecting the cutting edges of the cutters from injury while the reamer is being withdrawn. The tool may also be employed for the purpose of freeing and discharging detritus or accumulations of any kind in the well and for effecting its discharge in an obvious manner so as to remove any obstructions to the downward advance of the pipe string in service use.

My invention thus provides a device of the character described which may be employed in a ready and efficient manner for the purposes set forth, and which may be manufactured and sold at a low cost and operated in a convenient manner. Should it be desired to remove the tool, after removal of the well casing, it will be understood that this may be done in the manner above-described.

Having thus fully described my invention, I claim:

1. In oil delivery means for oil wells, an oil delivery pipe, an elongated plug at the intake end of the pipe, said plug being coupled to the pipe for connection and disconnection by relative rotation between the pipe and plug, said pipe having an annular series of longitudinal recesses in its periphery, cutters pivotally mounted at their lower ends in said recesses and having angularly arranged upper ends relatively converging in an inward and upward direction, the bodies of said cutters being provided with longitudinal cutting edges disposed by said inclined ends to incline at a downward and upward angle to the plane of the plug, and springs in said recesses and bearing against the cutters at the juncture of their inclined ends and inclined body portions, to yieldingly project the upper inclined ends of the cutters outwardly beyond the recesses, said spring-pressed upper inclined ends of the cutters being adapted for riding contact with the well wall for a yielding retraction of the cutters in the operation of withdrawing the plug with the delivery pipe from the well.

2. In an oil delivery means for oil wells, an oil delivery pipe, an elongated plug at the intake end of said pipe, said plug being coupled to the pipe for connection and disconnection by relative rotation between the pipe and plug and having a longitudinally tapered lower end and an annular series of longitudinal recesses in its outer periphery above said tapered end, cutters pivotally mounted at

their lower ends in said recesses and having angularly arranged upper ends relatively converging in an inward and upward direction, the bodies of said cutters being provided with longitudinal cutting edges disposed by said inclined ends to incline at a downward and upward angle to the plane of the plug, and springs in said recesses and bearing against the cutters at the juncture of their 10 inclined ends and inclined body portions, to yieldingly project the upper inclined ends of the cutters outwardly beyond the recesses, said spring-pressed upper inclined ends of the cutters being adapted for riding contact 15 with the well wall for a yielding retraction of the cutters in the operation of withdrawing the plug with the delivery pipe from the well.

In testimony whereof I affix my signature.
